UNITED STATES PATENT OFFICE.

JULIAN KENNEDY, OF LATROBE, PENNSYLVANIA.

HYDRAULIC MOTOR.

SPECIFICATION forming part of Letters Patent No. 423,563, dated March 18, 1890.

Application filed April 15, 1889. Serial No. 307,219. (No model.)

To all whom it may concern:

Be it known that I, JULIAN KENNEDY, of Latrobe, in the county of Westmoreland and State of Pennsylvania, have invented a new and useful Improvement in Hydraulic Motors, of which the following is a full, clear, and exact description, reference being had to the accompanying drawing, which shows a hydraulic cylinder and piston provided with

10 my improvement.

In the drawing, 2 is the cylinder.

3 is the piston-rod, which is preferably hollow, and 4 is the piston-head. The cylinder is preferably provided with a brass lining 5, which extends from end to end of the cylinder in a single piece, being constructed with its greatest diameter formed in an outwardly-projecting shoulder 6, and at the outer end of the lining there is an inwardly-projecting annular shoulder 7, which fits neatly around the piston-rod. The cylinder is provided with a cap 8 at its inner end and with a follower or gland 9 and suitable packing at the other end, and from the construction of the lining 5 it

25 follows that it may be removed from the cylinder in a single piece by removing the cap 8.

10 and 11 are the pipes by which water is admitted to and exhausted from the cylinder at either side of the piston-head. When the 30 work to be done by the hydraulic motor is large, the water-pressure exerted in the cylinder is necessarily very considerable, and it is desirable to use precautions against the leakage of water past the packing of the piston-head in the cylinder from one side of the piston-head to the other. To this end I provide the piston-head with two packing-rings *b* and *c*, which are separated from each other, preferably by an intermediate metal ring *d*,

40 and I connect the space between these packing-rings by vent holes or passages *e* with the interior of the hollow piston-rod. In case any water should leak past either packing *b* or *c* from either side of the piston, it will pass

45 through these vents into the interior of the piston-rod without passing to the other side of

the piston-head, and on its escaping from a suitable outlet *f* at the outer end of the piston-rod the presence of the leak may be promptly detected and measures taken to remedy it. 50

My invention consists in providing the piston-heads with vents in the manner just described; but it is not limited precisely to the construction of parts shown in the drawing, since modifications may be made therein by 55 the skilled mechanic to suit the needs of the particular apparatus with which my improvement is used.

The advantages of my invention will be appreciated by those skilled in the art. It is 60 simple in its construction and is perfectly reliable and efficient in its action.

I am aware of the following United States Letters Patent: No. 352,797, granted to C. W. Baldwin on November 16, 1886; No. 277,305, 65 granted to S. Maltby on May 8, 1883, and No. 323,749, granted to F. Stitzel on August 4, 1885; and I do not claim the devices therein shown and described.

I claim as my invention— 70

1. In a hydraulic motor, the combination of a cylinder and a piston or plunger having packings fitting against the interior of the cylinder and having a vent leading from between said packings and adapted to remove 75 leaking water, substantially as and for the purposes described.

2. In a hydraulic motor, the combination of a cylinder, a piston, and a hollow piston-rod, said piston having packings fitting against 80 the interior of the cylinder, and having a vent leading from between said packings to the hollow portion of the piston-rod and adapted to remove leaking water, substantially as and for the purposes described. 85

In testimony whereof I have hereunto set my hand this 10th day of April, A. D. 1889.

JULIAN KENNEDY.
